E. W. Anderson,

UNITED STATES PATENT OFFICE.

JOHN D. ENNES, OF NORFOLK, VIRGINIA.

RUBBER-DAM CLAMP.

SPECIFICATION forming part of Letters Patent No. 402,315, dated April 30, 1889.

Application filed September 20, 1888. Serial No. 285,943. (No model.)

To all whom it may concern:

Be it known that I, JOHN D. ENNES, a citizen of the United States, and a resident of Norfolk, in the county of Norfolk and State of Virginia, have invented certain new and useful Improvements in Rubber-Dam Holders; and I do declare the following to be a full, clear, and exact description of the invention, such as will enable others skilled in the art 5 to which it appertains to make and use the same, reference being had to the accompanying drawings, and to letters or figures of reference marked thereon, which form a part of this specification.

15 Figure 1 of the drawings is a representation of a front view of the holder applied. Fig. 2 is a perspective view of the holder. Fig. 3 is a vertical sectional view through the closed clamp. Fig. 4 is a similar section showing 20 the clamp open.

This invention has relation to holders for rubber dams for dentists' use; and it consists in the construction and novel combination of devices as hereinafter set forth, and pointed 25 out in the appended claims.

The object of the invention is to provide a holder which is simple and readily adjusted, which will not catch in the hair, and which will not injure the rubber.

30 In the accompanying drawings, the letter A designates the piece of rubber or dam, and B the holder or clamp. C is a piece of tape or braid which is used to secure the dam in position, being attached to the clamps and 35 extending around behind the head of the patient.

The clamp A consists of a base, D, of sheet metal having some elasticity, a broad angular jaw-piece, E, adjustable lengthwise of the 40 clamp A, and a removable pin or bar, F. The base D is formed with a lip, g, at its front portion, and at its back a hollow angular fold, h, the edge of which approximates the surface of the base. Through this hollow fold extends the wire or pin F, one end of which should be threaded, preferably, to receive a nut-head, k. When this head is taken off, the pin can be removed. In the back of the fold h is made a slot, l, at about the middle of the 45 length of the holder, and this slot has at its 50

end a narrow extension or offset, m. By means of the pin the braid is connected to the holder. The pin having been removed, a fold of the braid is introduced into the larger part of the slot, and then, the pin having been replaced, 55 extending through the fold of the braid, the latter is moved edgewise into the narrow portion or offset m of the slot, whereby it is secured.

To adjust the braid, slide it into the larger 60 part of the slot, and then it can be easily pulled in either direction to enlarge the loop around the head of the patient or to make it smaller, the adjustment being readily secured by moving the fold into the offset m.

65 The jaw-piece E is of broad form, and is made with a biting-lip, n, to engage the lip of the base, and with a V-form spring bent at its back portion, which passes under the edge of the back fold of the base. This bend e consists of a shoulder-piece, b, and a tongue, c, these parts meeting at the angle e, which impinges on the base. When the clamp-jaw is raised from the base to insert a piece of rubber, the angle e is protruded a little from under the edge of the fold h, so that the jaw is held in open position. When, however, the jaw is closed down, holding the rubber by its lip against that of the base, the angle e retreats under the edge of the back fold of the 80 base and the tongue portion c of the clamp within said back fold is sprung upward, and by its elasticity and that of the base the two lips are held closely pressed together upon the rubber. The jaw-piece E is preferably 85 made shorter than the base, and can be readily adjusted toward either end thereof without impairing the efficiency of its clamping power, and the length as well as the form of its biting-edge serve to obviate injury to the 90 rubber while securing a firm hold thereof.

Having described this invention, what I claim, and desire to secure by Letters Patent, is—

1. A rubber-dam holder consisting of a base- 95 clamp having a front lip and a slotted angular rear fold provided with an edge approximating said base, a clamp-jaw having a V-form rear portion engaging said fold and a biting- lip to engage the lip of the base, and a re- 100

movable pin in said fold, substantially as specified.

2. The combination, with the spring-base D, having an angular rear fold and front clamping-lip, of the longitudinally-adjustable clamp-jaw E, having a front lip, and a V-form rear portion consisting of a shoulder portion, b, and spring-tongue c, substantially as specified.

3. In a spring-jaw rubber-dam clamp, the

slotted angular fold of the base, having a removable pin extending through said fold, substantially as specified.

In testimony whereof I affix my signature in presence of two witnesses.

JOHN D. ENNES.
